UNITED STATES PATENT OFFICE.

EMILE BEDARD, OF PAWTUCKET, RHODE ISLAND, ASSIGNOR TO HEMPHILL MANUFACTURING CO., OF PAWTUCKET, RHODE ISLAND.

STOCKING-KNITTING MACHINE.

1,204,643.

Specification of Letters Patent. Patented Nov. 14, 1916.

Application filed April 11, 1914. Serial No. 833,295.

To all whom it may concern:

Be it known that I, EMILE BEDARD, citizen of the United States, residing at Pawtucket, Providence county, Rhode Island, have invented certain new and useful Improvements in Stocking-Knitting Machines, of which the following is a specification.

It is the object of my invention to provide a circular stocking knitting machine capable of widening beyond the point where narrowing began. Such machine is adapted to make what is known to the trade as the Hirner foot in which the widening actions are continued after the heel pocket is formed to 15 throw in additional widenings, the present invention being intended to accomplish the same general results as the machine described in an application for Letters Patent of the United States filed by George P. Bos- 20 worth, the stocking produced having among other characteristics a longer sole than instep, tending to make the foot assume a position nearer a right angle to the leg than is customary in a seamless stocking. 25 In the accompanying drawings Figure 1 is a front view of a knitting machine head of the Banner type disclosed in Letters Patent of the United States granted to Hemphill, #933,443, September 7, 1909; Fig. 2 is 30 a plan view of a portion of said head, this view being in the nature of a diagram; Fig. 3 is a sectional view showing a portion of the cylinder, and the instep cam arrangement made in accordance with my invention; Fig. 4 is a plan view of the switch cam for rendering the instep needles inop- 35 erative; Fig. 5 is a perspective view of the cam of Fig. 4; Fig. 6 is a diagrammatic view looking from the inner side of the 40 cam ring; Fig. 7 is a diagrammatic view of an ordinary stocking showing the heel and toe gores; Fig. 8 is a similar view of a stocking indicating the gore formed by the additional widenings from α to α ; Fig. 6^a is a detail.

In these drawings, 1 indicates the needle cylinder, and 2 the cam ring surrounding the same and mounted on the plate H of the Hemphill patent, which plate also carries the narrowing and widening pick mechanism. The narrowing picks are indicated at a , and the widening picks at b , being shown substantially of the Banner type, but the invention is not limited in this respect. In a machine of the Banner type a

half circle of long butt instep needles are employed, and a half circle of short butt heel and toe or sole needles. These short butts in usual practice extend out to the edge of the cam ring, while the long butts 60 of the instep series extend out beyond the outer face of said ring to be acted on by the ordinary lower instep cam which lies against the outer face of the cam ring, and which, when raised, elevates these needles of the 65 instep series to inoperative position while making the heel and toe on the other series of needles. The long butt instep needles in machines of the above mentioned type are not adapted for picking, and therefore in 70 my present machine I employ for the instep series a shorter butt needle than is customarily used, so that picking can be done on them, and I have shown these needles at c , Fig. 2, as being only as long as the ordinary short butt needle of prior practice reaching out to the edge of the cam ring 2, though it will be understood that the length of the butts of these needles may be varied 75 within certain limits. For the heel and toe 80 or sole series I employ needles with butts d which are shorter than the butts of the instep series c , and while the length of these butts d may vary within certain limits, in the particular construction shown these short butts 85 extend only half way across the upper edge of the cam ring.

For elevating the longer butt instep needles c to inoperative position I employ a switch cam 3. This may be constructed of 90 various forms and operated in various ways, but in the particular construction shown as exemplifying my invention this cam is pivotally mounted by being fixed to a shaft 4 journaled in a bearing 5 on the standard or 95 post 6 which is the usual support for the instep cam ordinarily employed. This shaft is rocked by an arm 7, link 8, lever 9, link 10 extending to a lever 11 operated by a cam 12 on the shaft 5' (see the Hemphill patent) of the pattern drum not shown. This switch cam 3 lies in a recess or depression 13 formed in the outer face of the cam ring 2, so that when raised it will engage the longer butt needles c as they pass over this 105 recess or depression in the cam ring, and thus these longer butt instep needles will be raised from their normal plane high enough to be engaged by the fixed lifting cam 14. This cam is supported on a stand- 110

ard 15 which, in turn, is supported on the plate H. As the needles of the long butt or instep series which have been particularly raised by the switch cam 3 pass over this fixed cam 14, they will be lifted all the way to their inoperative position, and heel and toe work then can be proceeded with. The usual upper cam 16 of the instep set, which is used for returning the instep needles down to their normal plane for round knitting, is as usual mounted on a block 17 slideable vertically, in the standard or guide 6, said block being operated by a bell crank lever 18 pivoted at 19 and operated through 15 a link 20 from the clutch lever b' of the Hemphill patent.

In the operation of the machine when heel and toe work is to be done, the bell crank lever 18 is operated at the same time that the lever b' of the Hemphill patent is operated to change the drive from round knitting to reciprocating knitting. This bell crank lever will therefore lift the upper instep cam 16 and at the same time the switch cam 3 will be tilted up to raise the longer butt instep needles c by acting directly thereon, and moving them high enough to be acted on by the fixed cam 14, which completes their elevation to inoperative position. This cam 30 3 is tilted up when the shorter butt needles are passing it, and thus it gets in position for raising the long butt needles when they come around. Having raised the instep needles c, the switch cam 3 falls back to 35 normal position. Narrowing now goes on by the narrowing picks raising the shorter butt needles d from the ends of the column of active heel and toe or shorter butt needles d and adding them to the column 40 of inoperative instep needles c. Now, when widening takes place the widening picks will throw down the short butt needles d which were picked up for narrowing, the picking action for widening being performed in the 45 ordinary way by the widening picks, but instead of stopping the widening actions when the point is reached where narrowing began, as is the usual practice, I continue the widening by keeping up the reciprocating movement of the cylinder, and by using 50 the longer butt instep needles with butts of a length equal only to the length of the short butt needles, as heretofore used in machines of the Banner type, and which, 55 of course, are of the proper length for picking. In other words, in my present improvement I use as my longest butt needles the ordinary short butt needles heretofore

used, or approximately this length, while for short butt needles I employ needles having a shorter butt.

To put the invention in another way, I use for the instep series needles having butts as long as it is practicable to pick, while for the heel and toe needles I use butts enough shorter than those of the instep needles to enable an instep cam to work on the instep or longer butt needles directly without affecting the short butt needles.

I claim as my invention:—

1. In combination in a stocking machine, a needle cylinder having rotary and reciprocating movements, needles arranged in two series one having longer butts than the other, a fixed cam ring surrounding the cylinder having a recess in its outer side, the long butt needles extending substantially to the edge of the cam ring and over the recess and the short butts part way across the cam ring, a vertically movable cam located in said recess and engaging, when raised, the longer butt needles to elevate them for making them inoperative, narrowing pick mechanism and widening pick mechanism operative upon both the short and the long butt needles to widen the fabric, and automatic means for operating the pivoted cam, substantially as described.

2. In combination, a rotary needle cylinder, short butt heel and toe needles, longer butt instep needles, a fixed cam ring, a stationary post, a needle lowering cam slidably mounted in said post and movable vertically, a vertically movable instep cam for engaging only the long butt needles, said cam engaging said butts directly, narrowing pick mechanism, widening pick mechanism, the latter picking both the short butt and the long butt needles and continuing the picking for widening after the widening has been performed on the short butt needles to the point where narrowing began, and automatic means for operating the instep cam to raise the long butt needles and for retracting said cam before widening begins on the long butt needles, said instep cam having pivotal movement, and a rock shaft mounted on the fixed part of the machine and carrying said cam with means for operating the rock shaft, substantially as described.

In testimony whereof, I affix my signature in presence of two witnesses.

EMILE BEDARD.
